[57] CLAIM

The ornamental design for a rotating storage and display device, as shown and described.

DESCRIPTION

FIG. 1 is a perspective view of a rotating storage and display device containing cards and brochures which, being no part of the design, are shown in phantom;

FIG. 2 is a side elevational view thereof, being representative of all sides of the design;

FIG. 3 is a top plan view thereof; and,

FIG. 4 is a bottom plan view thereof.
